SLIP

Victor L. Sussberg, New York, N. Y.

Application June 22, 1934, Serial No. 731,977

3 Claims. (Cl. 2-73)

This invention relates to garments and particularly to what is known as a slip, the object being to provide an improved construction which will automatically fit itself to a figure whether the figure is slightly larger or smaller than the garment.

Another object of the invention is to provide a slip wherein the front and back panels are arranged on the bias or diagonal, with the seams 10 at the sides, so that the body of the garment may take the correct position when in use.

A further object of the invention is to provide a slip with an upper end or brassière section which presents front and rear panels independent of the body but connected thereto so as to present the desired support for the busts without interfering with the proper fit of the body.

In the accompanying drawing—

Figure 1 is a front view of a slip disclosing an embodiment of the invention;

Figure 2 is a rear view of the slip shown in Figure 1;

Figure 3 is a perspective view of the slip shown mounted on a figure.

Referring to the accompanying drawing by numerals, 1 indicates the body of the garment, and 2 the brassière section, said brassière section merging into the body in a uniform manner. The body 1 is made up of front and rear panels 3 and 4 cut, so that the yarn will be on the bias, diagonally. This will allow the body to properly drape itself when mounted on a figure, as shown in Fig. 3, whereby a comparatively slender or a comparatively stout person may wear the garment and the garment will be caused to fit properly.

As shown in Figs. 1 and 2, the brassière section extends from the upper part of the garment downwardly a certain distance, and then abruptly stops. The lower end portions of the brassière section present a truncated triangular shaped construction having curved ends so that the brassière section and body may conform properly to the figure of the person wearing the garment without distortion. By forming the brassière sections as above set forth comparatively stout persons may readily use the slip and it will act to present a continuous, even, curved line across the waistline and thence downwardly, thus giving in a limited sense a molded effect as illustrated in Fig. 3.

As illustrated particularly in Fig. 3, the waistline 5 is suggested but there is no definite line and, consequently, a pleasing appearance is provided without distorting the garment. The bras-

sière section 2 is formed from what may be termed front panels 6 and 7 and rear panels 8 and 9. These panels are connected together along the respective sides by suitable seams 10 and 11, which seams extend downwardly to the bottom 80 of the garment and present the front and rear panels 3 and 4, together. It will, therefore, be seen that the seams on the body are at the sides and that they are a continuation of the seams which connect certain parts of the brassière panels together. Each brassière panel at the lower end is formed with an arc-shaped edge 12 secured by the stitching 13 to the body 1, and the respective panels are secured by the stitchings 14, 15, 16 and 17 to the extending A-shaped projections 70 18 and 19 of the body, as shown in Figs. 1 and 2. The parts are so proportioned that the adjacent portions of the brassière panels 8 and 9 may overlap above the A-shaped projection 19; though this is not essential. However, the seams 16 and 17 at 75 the top of the A-shaped section 19 merge into seam 20 for connecting the adjacent portions of the brassière panels 8 and 9 together. At the front the same idea is presented, namely, the seams 14 and 15 merge into seam 21 for connecting the panels 6 and 7 above the A-shaped extension 18 in a similar manner to the way seam 20 connects panels 8 and 9 together above projection 19. This provides a very strong connection and is adapted to take up quite a strain. The front panels 6 and 7 are intended to act in a limited sense as breast pockets with the lower edges 12 positioned below the busts and with the projection 18 yielding to secure a proper fit. At the rear the panels 8 and 9 and section 19 will 85 adjust themselves automatically with the back, and this adjustment will not affect the body 1 because of the diagonal cut of the panels and the body.

The arrangement of the panels as just described with their curved lower edges immediately below the busts, secures a proper fit around the busts and at the same time does not distort the garment at the waistline portion 5 whereby the waistline may automatically stretch laterally or vertically to present a proper contour to the body and round out certain parts thereof so that a uniform and more or less molded appearance will be presented, as clearly shown in Fig. 3. By providing this appearance to the slip or undergarment presented, a dress applied thereover will naturally take on the same contour or shape and present the desired appearance.

As illustrated in the drawing, there are provided shoulder straps 22 which are connected to 110

the highest point on the respective panels 6 to 9, inclusive. It will be noted that the upper part of the panels are substantially A-shaped and by reason of this shape the seams 20 and 21 are positioned comparatively low, so that a modestly low cut dress, both front and back, may be worn without disclosing the slip.

I claim:—

1. A slip made of bias cut material comprising a body having front and rear panels, said front panel having at the top an A-shaped central projection extending longitudinally of the garment and an arc-shaped convex edge on each side of said A-shaped projection, and a brassière section connected with the upper end of said body, said brassière section being formed with a pair of front panels fitting against said arc-shaped edges and against said A-shaped projection, each of said panels of the brassière section at the bottom portion being formed as a truncated triangle with the bottom edges of the brassière section shaped to conform to the shape of said arc-shaped edges of the body.
2. A slip made of bias cut material comprising a body having front and rear panels, both of said panels having at the top an A-shaped central projection extending longitudinally of the garment and an arc-shaped convex edge on each side of each of the A-shaped projections, and a brassière section connected with the upper end of said body, said brassière section being formed

with a pair of front and a pair of rear panels fitting against said arc-shaped edges and respectively fitting against the sides of said A-shaped projections, each of the panels of the brassière section at the bottom portion being formed as a truncated triangle with the bottom edges conforming in shape to said arc-shaped edges, the respective panels of the brassière section at the sides of the garment abutting, and a seam at each side of the garment extending from the top of the brassière section to the bottom of said body.

3. A slip made of bias cut material comprising a body having front and rear panels, said front panel having at the top an A-shaped central projection extending longitudinally of the garment and an arc-shaped convex edge on each side of said A-shaped projection, a brassière section connected with the upper end of said body, said brassière section being formed with a pair of front panels fitting against said arc-shaped edges and against said A-shaped projection, each of said panels of the brassière section at the bottom portion being formed as a truncated triangle with the bottom edges of the brassière section shaped to conform to the shape of said arc-shaped edges of the body, said brassière sections extending above said A-shaped projection, and a seam above said A-shaped projection for connecting said brassière sections together.
